UNITED STATES PATENT OFFICE.

JOSEPH EISENMANN, OF LONDON, ENGLAND.

DESIGN FOR A DOLL.

43,868.

Specification for Design.

Patented Apr. 22, 1913.

Application filed December 23, 1912. Serial No. 738,377. Term of patent 3½ years.

To all whom it may concern:

Be it known that I, JOSEPH EISENMANN, a subject of the King of Great Britain, residing at London, England, have invented a new, original, and ornamental Design for a Doll, of which the following is a specification, reference being made to the accompanying drawing, forming part thereof.

The figure is a front view of a doll showing my new design.

I claim:

The ornamental design for a doll.

JOSEPH EISENMANN.

Witnesses:

O. J. WORTH,
C. P. LIDDON.
